UNITED STATES PATENT OFFICE.

MIRABEAU SIMS, OF LLANERCH, PENNSYLVANIA, ASSIGNOR TO SIMS AUTOMATIC CONVEYER COMPANY INCORPORATED, A CORPORATION OF DELAWARE.

TRANSLATING AND COOLING MATERIAL.

1,300,784.

Specification of Letters Patent. Patented Apr. 15, 1919.

Application filed September 4, 1915. Serial No. 49,102.

To all whom it may concern:

Be it known that I, MIRABEAU SIMS, a citizen of the United States, residing at Llanerch, in the county of Delaware, State 5 of Pennsylvania, have invented a new and useful Improvement in Translating and Cooling Material, of which the following is a specification.

My invention relates to improved method 10 and means for translating and cooling material. The invention is especially applicable to the treatment of bone black used in connection with sugar refining. After this bone black has been used in the sugar refining 15 process it is recovered, dried in kilns, reduced to the required temperature for the refining process and returned to the refining apparatus. The method of withdrawing, drying, cooling and returning the bone black 20 to the refining apparatus has been heretofore complicated and expensive. The object of the present invention is to provide simple and efficient method and means for accomplishing this object.

25 Referring to the drawings which illustrate merely by way of example apparatus suitable for effecting this invention:—

Figure 1 is a side elevation of such apparatus.

30 Fig. 2 is a transverse elevation of same.

Fig. 3 is a side elevation of a detail on an enlarged scale, showing the hopper mounted on a section of conveyer pipe.

Fig. 4 is a plan view of same.

35 Fig. 5 is an end elevation.

Similar numerals refer to similar parts throughout the several views.

As is well known, bone black or animal charcoal is used in the refining process of 40 making granulated sugar, and after such use, it is recovered and transferred to driers or kilns for drying the same. It comes out of the driers or kilns at a temperature approximately 400° F. The temperature of 45 the material must be reduced to about 120° F. before it can be returned to the refining apparatus. In common practice the bone black is dropped from the kiln, at intervals, in a stream about three inches in diameter.

50 This stream runs for about six seconds and is interrupted for about twelve seconds. This intermittent operation continues during the entire twenty-four hours of the day. A number of kilns are operated at the same 55 time.

By the method and means comprised in the present invention, the driers or kilns are indicated at 7. These kilns are adapted to deliver to hoppers 8 arranged successively along the conductor or conveying pipe 60 9. Each hopper 8 is so proportioned relatively as to hold an amount of material equal to about a thirty minutes' flow from the kiln. At the bottom of the hopper are provided double sliding gates 10, meeting 65 on the diagonal line 11 as shown in Fig. 4. The purpose of this diagonal line of separation between the gates 10 is to increase the distribution of the material over the screen 13. These gates are adjustable by means of 70 the handles 12, for permitting the proper flow of material past the same to the screen 13, which in the present example, is provided by the series of perforations 14 in that part of the wall of the pipe 9 inclosed 75 within the bottom margin of the hopper 8; the screen serving to intercept the particles of brick, broken off from the kiln in the drying process, which are undesirable to be retained in the bone black. It will be un- 80 derstood that the sliding gates 10 are so adjusted as to permit a sufficient feed to the conveyer pipe to take care of the intermittent feed from the kiln.

In the present example it has been found 85 convenient to provide the conveyer pipe approximately fifteen inches in diameter, and extending approximately 150 feet horizontally and 113 feet vertically. This pipe is provided at the top with the return bend 90 16, having its downwardly projecting discharging end flaring as at 17, and inclosed within the chamber 18. Chamber 18 is connected at its top by conductor 19 with the suction producing blower 20. The chamber 95 18 is adapted to discharge at the bottom to the chute 21, which delivers to the carrying belt 22, which transports and delivers the bone black back to the refining apparatus, not shown, at the required temperature. A 100 suitable valve control for the discharge from 18 to 21 is indicated at 23.

The operation of the device is as follows:—

The lower portions of the driers or kilns 7 105 are only shown diagrammatically, as their construction and operation are well known and need no description here. The bone black, after it has been used in the refining apparatus and has been withdrawn there- 110

from, is delivered by any suitable means to these kilns where it is thoroughly dried. In the process of drying the material, its temperature as above stated, is raised to about 5 400° F. and before it can be returned back into the refining apparatus this temperature must be reduced to 120° F. As the material falls from the driers into the hoppers and especially against the metallic walls thereof 10 and the adjustable gates therein, the first stage of cooling begins. A further cooling is effected by the material encountering the perforated walls of the conducting pipe 9. A further cooling takes place as the material 15 encounters the inrushing air drawn upwardly from the intake end 24 to the chamber 18. A further cooling takes place as the material travels along this horizontal and conveyer pipe 9 and as it is discharged 20 through the chute 21 onto belt 22 and as it is carried along the belt 22. The speed of travel of the material from the kilns 7 to the chamber 18 depends upon the velocity of the air current through the pipe 9 and 25 also upon the specific gravity of the bone black. The air velocity of course can be regulated as for example, by means of the rheostat 25 controlling the speed of motor 26 which drives the blower 20. In this way 30 the required length of time may be consumed

in translating material from the kilns to the belt which may be required for the several factors herein mentioned to reduce the temperature of the material from that at which it is delivered from the kilns to that 35 required when it is delivered to the refining apparatus.

What I claim is:

Apparatus for operating upon bone black after its use in the refining of sugar, which 40 comprises a drying kiln adapted to discharge its contents intermittently, a pneumatic conveyer pipe of sufficient extent to secure a substantial cooling of the material discharged from the kiln, said conveyer pipe 45 provided with a plurality of apertures through which the material is introduced thereto, means for converting the intermittent discharge from the kiln to a substantially constant flow into the pipe, regulatable means for inducing a current of air through the pipe, a conveyer belt and means for discharging the material from the pipe to the belt, whereby the material is reduced in 50 temperature from that of the kiln to the temperature required for reuse at the discharge end of the conveyer belt.

MIRABEAU SIMS.
